PULL POINTING MACHINE

Ernest Willett, Gary, Ind.

Application November 6, 1947, Serial No. 784,323

3 Claims. (CL. 207—1)

1

This invention relates a new and useful method of pointing metal or other bars and machine for pull pointing the same, so that a section or area of the bar undergoing the application of heat may be pulled in opposite directions from the point where it is heated, the pulling force exerted in opposite directions causing elongation of the bar at the heated portion while at the same time pulling the portions at opposite sides of the heated part of the bar away from each other in opposite directions so that the resultant elongation continues until the metal bar separates or bisects in such a manner as to leave points on the bisected, separated, or severed ends of the bar.

Another object of the invention is to provide a power driven machine for carrying out the method of pointing metal bars, including opposed gripping means actuated by cams or eccentrics to cause opposed grippers to grip the bar upon opposite sides of an intermediate portion of the bar undergoing the application of heat and at the same time, to pull thereon in opposite directions outwardly or away from each other, so that the combined pulling and heating causes resultant elongation of the bar until it separates or bisects in such a manner as to leave points on the bisected, separated or severed ends of the bar or rod for any purpose for which the same is adapted.

Another object of the invention is to provide a new and useful method of pointing metal bars, in which heat is applied to a portion of the bar within its length, and a portion undergoing the application of heat is caused to be elongated by pulling on the bar at opposite sides of the heated portion and in opposite directions outwardly while being gripped, preferably by opposed sets of grippers caused to take outward movement by opposed eccentric wheels, so that the heated portion is elongated and continues until the metal bar or the like, separates or bisects in such a manner that as the pull progresses, the drawn point is produced at each end of the bisected, separated or severed ends of the bar, so as to leave points of tapered uniform and smooth formation capable of use for which any tapered or drawn point may be employed, such as in bearing pintles, valve stems or otherwise.

Other objects and advantages reside in the details of construction and operation as more fully hereinafter described and claimed, reference being had to the accompanying drawings forming part hereof wherein like numerals refer to like parts throughout, and in which:

Figure 1 is a top plan view of a pull pointing machine for pointing metal bars, constructed in accordance with the invention;

2

Figure 2 is a side elevation partly broken away and in section;

Figure 3 is a sectional elevation taken on the staggered section line 3—3 of Figure 1, with the eccentrics in elevation as well as the bearings for the shafts thereof; and,

Figure 4 is a horizontal sectional elevation with portions broken away, one of the eccentric wheels being shown in section and the other in elevation 10 as viewed substantially on the staggered section line 4—4 of Figure 2.

Referring to the drawings in detail, the machine for pointing metal bars or pull pointing machine of the present invention for practicing the method comprises a machine bed 10 of elongated rectangular construction shown made up of elongated sides and ends 11 and 12 respectively welded or otherwise joined at the diagonal corners 13 to provide an opening vertically therethrough 14 as indicated at 14 from top to bottom and recessed at the top flanges at the end channels 12, as indicated at 15 for a purpose to be hereinafter made apparent. Bolted at the sides 11 intermediately of the ends thereof as at 16, in vertical positions, are stabilizer bearing supports 17 arranged at opposite sides and extending outwardly therefrom to support in connection with the vertical end flanges 18 thereof, a flat top plate 19 which may be welded thereto as indicated at 20, so as to project beyond the ends of the stabilizer bearing supports 17 at the ends or flanges 18. Guide bars 21 are mounted transversely on the plate 19 of the stabilizer bearing supports 17 in spaced parallel relation slightly inwardly of and parallel to the ends or flanges 18 to extend across said plates and may be secured in position by suitable machine screws or the like 22.

The machine bed 10 upon opposite sides thereof, upon the top flanges of the channels 11 slightly outwardly of the aligned end edges of the plate 19, supports suitable pillow block bearings 23 which may be bolted to the said flanges of the machine bed, as indicated at 24 through the base lugs or flanges thereof to rotatably support horizontal parallel shafts 25 against end thrust. One end of each shaft 25 projects and may be equipped with a suitable key or spline as indicated at 26, or other suitable means for operative connection with a suitable prime mover or drive means, and shown as a pulley 27 keyed thereon and driven by an endless drive member 28, although it is understood that any other suitable drive means may be employed for this purpose whereby power may be delivered to the shafts 25 for rotating the same simultaneously in opposite directions as indicated by arrows in Figures 2 and 3 of the

drawings downwardly at the inside. Each shaft is provided with an eccentric wheel or cam 29 fixed thereto in any suitable manner to rotate therewith and shown as comprising a disc with a hub 30 fixed or keyed to the shaft as indicated at 31 and provided with a peripheral flange 32 projecting outwardly intermediate opposite camming or eccentric flanges or surfaces 33 in the form of circular flanges correspondingly tapering to zero at the flange 32 as indicated at 34 in convex form and gradually widening to the point 35 substantially entirely around the circumference and then approaching the zero point or flange 32, as indicated at 36 in a comparatively abrupt taper or angle. That is, the abrupt curvatures 36 approach the opposite sides of a central annular flange on the periphery of each eccentric at a relatively sharp angle in spaced relation to the gradually tapered ends or portions 34 where they approach the opposed faces of the flange 32. It should also be noted that the recesses 15 accommodate the flanges 32 and adjacent portions of the eccentric flanges or surfaces 33 extending laterally in opposite directions from opposite sides of said flange 32.

Mounted to slide in and out of the guide bars 21 are toggle box holders 37 in the form of horizontal flat plates in spaced parallel relation to the plates 19, there being four of such holders, or two sets of two each in spaced relation to the transverse center of the machine bed which latter is left open as indicated at 38 to provide an area for heating a portion of the work piece or metal bar to be severed and formed with tapered, pointed or conical ends, as will be hereinafter more fully set forth. The toggle box holders or plates 37 are provided over the guide rails or tracks 21 with upwardly extending apertured lugs or bearings 39 and the holders or plates 37 are provided with seats or grooves 40 which in conjunction with the lugs or bearings 39 serve to retain toggle boxes 41 on the holders 37 in spaced relation but so as to move in and out with the holders or plates 37 on the guide rails 21. The lugs or bearings 39 receive and confine in the openings or seats therein, the inner ends of guide rods 42 which extend through stabilizing bearings 43 mounted along the outer ends of the plates 19 or stabilizer bearing supports formed thereby and having their base portions 44 secured to said plates or supports 19 as by machine bolts or the like 45. The cap plates of the bearings 43 are removably secured in position as by means of machine screws 46 and the guide rods 42 bear resilient biasing means or coil springs 47 between the bearings 43 and the lugs or bearings 39 of the holders or plates 37 tending to normally force the latter and the toggle boxes 41 mounted thereon inwardly toward each other at the respective opposed pairs of such holders and boxes. The inner sides of the boxes 41 are provided with outwardly bevelled projections or bosses 38 having horizontally elongated slots 49 therethrough and extending into the cavities or hollowed out portions 50 of the boxes at the inner sides of the latter. At their outer sides, the boxes are provided with horizontal counterbores 51 in alignment with the slots 49 with reduced outer bores 52 forming shoulders or seats at the outer ends of the counterbores 51 through which compression bars 53 extend to move in and out but are normally held in by resilient biasing means or coil springs 54 mounted on the bars 53 against stops formed by enlarged portions or heads 55 formed at the inner ends of the bars 53 within the cavities 50 and counterbores 51 through which the bars 53 extend with the springs 54 confined between the shoulders at the outer ends of the counterbores 51 and the stops or heads 55 to normally force the bars inwardly. The power from the eccentric wheels or discs 29 having the annular eccentric flanges 33 is delivered to a toggle mechanism for actuating the work piece or metal bar grippers and holders to be later described, and comprising a tripper link 56 having a rounded inner end and extending movably through a slot 49 as seen more particularly in Figure 1 of the drawings. A fixed link 57 is pivoted at its outer end on a threaded pin 58 at the outer end of the cavity 50 of each toggle box 41 and is pivotally connected by a freely movable pin 59 to the outer end of the tripper link 56 and the corresponding outer end of a sliding link 60 within the inner angular portion or extension of the cavity 50 at which point it is connected to or engaged by the compression bar 53 which obviously may be pivoted or pivotally connected to the pin 59 or merely abut the outer end of the tripper link 56. The inner end of the sliding link 60 is pivotally connected as at 61 to each gripper jaw 62 at the inner end of each toggle box 41, said jaws being recessed centrally of the length of their jaw engaging faces lengthwise thereof as indicated at 63 and vertically, to conform to the work piece or bar B to be pull pointed. The work piece or bar B is also designed to rest in V-shaped jaws or notches 64 of work piece guides 65 projecting up from the holders or plates 37 at each side thereof above the sides of the machine bed 10 aligned with the opening 38 and spaces between the sets of boxes 41 in position so that the gripper jaws 62 can properly grip or grasp the same. The connection of the sliding, movable or pivoted link 60 with each gripper jaw 62 is effected through the medium of central outwardly projecting shanks 66 of the gripper jaws 62 extending through slots or openings 67 at the inner sides of the toggle boxes 41 and the outer sides of the boxes 41 are provided with bosses or lugs 68 if desired through which the bores 52 extend, either one or two of the compression bars 53 being provided as desired and located in line with the links 56 or 59 and 60, or above and below the same as desired. These lugs or bosses 68 are provided centrally at the outer sides of the boxes as seen in Figure 2 of the drawings and may constitute anchoring means for the boxes in abutment with the outer edges of the lugs or bearings 39 to guide the boxes in their inward and outward movements and retain them against inward movement at right angles thereto toward the work piece or bar being acted upon. Each box is provided with a cover 69 secured in position by machine screws or bolts 70 to retain the toggle assembly in position. Primarily, the lugs or bearings 39 take the thrust of the springs 47 and the guide rods 42 by reason of being formed integral with the holders or plates 37 and bearing against the outer sides of the toggle boxes 41 which move in and out with the holders 37. Of course, the rods 42 are confined or anchored in the bearings 39 and the springs 47 are confined between the latter and the bearings 43 as noted on the rods 42, while the rods 42 move in and out in the bearings 43 as indicated in Figure 1 of the drawings. Thus, the toggle boxes move in and out in a horizontal plane in both the pull and return strokes on the guide rails 21 and are nor-

inally urged in by the springs 47, together with the gripper jaws 62 carried thereby.

Thus, in the operation of the machine in accordance with the method of pointing metal bars or pull pointing as described, the work piece or bar B is laid in position upon its holder or work piece guides 65 over the stabilizer bearing supports or plates 19 transversely between the eccentric wheels 29, the spaces between the toggle boxes and mechanism therein and between the opposed gripper jaws 62 arranged in pairs upon opposite sides of the opening 38 and across the center of the latter between the peripheral edges of the wheels 29 or flanges 32 thereof. Power is then applied to drive the shafts 25 and eccentric wheels 29 in opposite directions with the eccentric members or flanges 33 which are alike, in corresponding positions, as clearly shown in the drawings. As the eccentric wheels are driven, their eccentric surfaces or edges 34 are caused to act on the cooperating tripper links 56 to force them outwardly and straighten out the links 57 and 60 in alignment longitudinally or sufficiently to force the gripper jaws 62 of the respective pairs or sets toward each other to grip the work piece or bar B upon opposite sides of the central portion at the opening 38, where the same is exposed to heat from a torch, gas flame or other suitable means for the purpose. In this operation, the links 57 and 60 are forced outwardly at their pivoted ends at the pivots 59 against the action of the springs 54 which normally hold them inwardly to project the links 56 against the eccentrics, thus compressing the springs 54 and forcing the inner ends of the links 60 to slide inwardly in the cavity, thus projecting the gripper jaws 62 inwardly into gripping position to grasp the work piece or bar B by reason of the pivots 61 moving inwardly toward each other and transferring such movement to the gripper jaws 62 to hold the metal bar or work piece during the pulling operation. As the eccentrics or eccentric wheels continue to rotate, the tripper links 56 are forced into the toggle boxes or slots of the bevelled bosses or inclined projections or camming surfaces 48 and the eccentric wheels engage the latter to force the toggle boxes outwardly to separate the same while sliding in a horizontal plane on the guide bars 21 and thus moving the gripper jaws 62 outwardly in opposite directions with respect to the two sets upon opposite sides of the point at which the portion of the work piece or bar B is heated thus compressing the springs 47 and moving the rods 42 outwardly through the bearings 43. As the toggle boxes and jaws are forced apart, pull thereby produced is exerted on the two portions of the bar at opposite sides of the heated portion reduced to a melted or soft condition which also may be produced electrically if desired. As this pull progresses, the drawn points are produced at the inner ends of the sections or portions of the rod or bar thus heated, the pulling, heating and resultant elongation continuing until the metal bar separates or bisects in such a manner as to leave points on the bisected, separated or severed ends of the bar drawn to a point, taper or cone as described. As the eccentric wheels continue to rotate, the springs 47 act to move the toggle boxes inwardly toward each other after passing the widest portions of the eccentrics or cams in one complete revolution until they pass the said widest portions 35 and approach the sides of the flanges 32 at the abrupt curved portions 36 to return to their initial position. The

springs 54 also disalign or break the toggle joints to retract the grippers and force the tripper links 46 against the opposite sides of the flange or peripheral portion of the eccentric wheels 29 or discs forming the same, thus freeing the tapered sections of the rods thus drawn and pulled apart to point the inner ends thereof. By this means, the action is automatic and is ready for another operation by automatic return to the original position of the entire puller assembly, with the toggle boxes moving inwardly on the guide bars or tracks 21 and the toggle mechanism and grippers moving therewith toward each other for a repeat of the same operation upon insertion and heating of a new work piece or bar.

Thus, it will be seen that I have provided a very efficient, simple and desirable machine and method for exerting opposite pull or stresses outwardly on the end portions of a work piece or bar of metal or the like or other material, away from a heated area, section or portion thereof to cause the same to be drawn to a taper or point of conical or other desired formation, in a quick and efficient manner whereby such operations may be very economically carried on. The machine is very low and comparatively flat so that it may be easily mounted upon a horizontal work surface, thus producing a very stable and desirable machine and method for the purpose and where the operation and progress thereof may be easily observed.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A bar pull pointing machine comprising a bed, opposed eccentric wheels rotatably mounted in the bed, means for driving said wheels in opposite directions, means actuated by said eccentrics to grip the bar at points upon opposite sides of an area in the length of the bar heated to a soft condition to permit elongation and separation thereof, means to exert opposite pull upon said gripping means, means for releasing the pull and grip on the separated end portions of the bars and means for moving said pulling means and gripping means toward each other to their original positions.

2. A pull pointing machine for bars, comprising a bed, eccentric wheels rotatably mounted in the bed and oppositely positioned to be driven toward each other in opposite directions, means for driving said eccentric wheels, a space between said wheels providing an area at which the bar is to be heated, means for supporting the bar over said space across the bed, toggle means movable in opposite directions on the bed and actuated by said eccentric wheels, grippers actuated by said toggle means to grip the bar upon opposite sides of the heated area and actuated by the eccentric wheels to cause opposite pull on the bar on opposite sides of the heated area to elongate and separate the bar and leave points on the separated ends, means to return said toggle means to its initial position upon release thereof

by the eccentric wheels in certain positions of the latter when the pull is released upon release of the grippers, and means for automatically causing the toggle means and gripping means to move toward each other to initial gripping and pulling positions after the pull and grippers have been released.

3. A pull pointing machine including a base frame, grippers mounted on said frame in spaced relation and opposing each other in pairs to grip a bar, means for supporting a bar across the frame in position to grip at spaced points upon opposite sides of an area in the length thereof, said area adapted to be heated to a soft condition such that opposite pull thereon on opposite sides of said area will cause resultant elongation of the bar and separation in such a manner as to leave points of tapered form at the separated ends, means for causing said grippers to grasp the bar and exert opposite pull thereon at such points and then to release the same upon the ends being separated, means for guiding said grippers in their movements upon the frame, spring means causing the release of the grippers when the ends have been separated, spring means

5

on the frame to cause the grippers to be moved inwardly toward each other upon release of the grippers and separation of said ends, said gripper moving and separating means including eccentric wheels having gradually tapered eccentric flanges upon opposite sides of the heated area and acting outwardly in opposite directions to cause outward pull of the grippers in opposite directions and toggle mechanisms between the grippers and the eccentric flanges to cause the gripping of the bar by said grippers and release thereof when the ends of the bars have been separated and pointed to move inwardly toward each other.

ERNEST WILLETT.
